CORSET

Joseph J. Kispert, Hamden, Conn., assignor to
 I. Newman & Sons, Inc., New Haven, Conn., a
 corporation of Connecticut

Application February 28, 1936, Serial No. 66,164

1 Claim. (Cl. 2—39)

This invention relates to corsets provided with lacing, and has for an object to provide an improved construction wherein covering flaps are provided for the lacing arranged to permit the lacing to have any desired adjustment and for covering the eyelets or other means carrying the lacing.

An additional object is to provide a corset which may be of the wrap-around type or the type open at the front and back wherein means are provided for covering all or part of the lacing and the metal or other parts connecting the lacing with the body of the corset.

A further object, more specifically, is to provide covering flaps for corsets wherein the flaps are stitched down at spaced intervals to provide a uniform smooth surface.

An additional and further object is to provide a covering flap for covering the eyelets or other members carrying the lacing, the flaps being formed with stiffening and retaining stays and stitching at spaced intervals extending through the stays, whereby the flaps are maintained smooth throughout.

In the accompanying drawing—

Fig. 1 is a front view of a corset disclosing an embodiment of the invention, the same being shown on a figure;

Fig. 2 is a front view slightly in perspective of the corset shown in Fig. 1, the same being on an enlarged scale;

Fig. 3 is a fragmentary sectional view through Fig. 2 approximately on the line 3—3, the same being on an enlarged scale;

Fig. 4 is a fragmentary enlarged sectional view through Fig. 2 on the line 4—4;

Fig. 5 is an enlarged fragmentary sectional view through Fig. 2 on the line 5—5;

Fig. 6 is an enlarged view partially in perspective illustrating how the flaps are held down and how they cover the various lacing-receiving eyelets;

Fig. 7 is a horizontal sectional view through a modified form of corset where a conventional lacing means is provided at the front and a lacing with flaps embodying the invention is arranged at the back.

Referring to the accompanying drawing by numerals, 1 indicates the body of a corset of substantially any desired type which is open at the front. This body extends across the back, the sides and across the front, or partly across the front, according to circumstances. The front portions 2 and 3 of the body 1 are spaced apart and the front portion 3 is provided with a spaced

section 4 connected to the main front portion 3 by a lacing 5. Suitable conventional fastening means 6 disengageably connect said section with the front portion 2. It will also be noted from Fig. 2 that the front portion 3 is cut away as at 7 and the front hose supporters 8 and 9 extend upwardly to the respective shoulders 10 and 11. By this arrangement an extra length of elastic is provided which will hold down the front of the corset without any undue strain.

As illustrated particularly in Figs. 3 and 6, the front section 3 is provided with an extension 12 having a row of eyelets 13, and adjacent the edge of the extension a reinforcing stay 14 formed of material through which stitching 15 may extend, is provided. This stay is formed of some composition or material that will permit a needle to readily pass therethrough when stitching 15 is applied. This form of stay is old and well known but the location thereof at the outer edge of the extension 12 is new. Coacting with the extension 12 is an extension 16 forming part of the section 4. A row of outlets is carried by the extension 16 and is covered by a flap 18 which has one portion secured in place permanently to the extension 16. Likewise a flap 19 covers the extension 14. In Fig. 6 the flap 19 has been shown as being pulled away from the extension 12. The parts are rather exaggerated in this figure so as to illustrate the fact that there is a space into which the lacing 5 may extend. It will be understood that the lacing extends over the extension 12, as shown in Fig. 6, through the various eyelets 13, and then in back of the extension 12 to a position in back of extension 16, through eyelets 17 in back of flap 18, and then through the open space, as shown in Fig. 2, back to the extension 12. The lacing is positioned in the ordinary way of lacing and will function properly to draw and hold the sections 2 and 3 together or in juxtaposition without the flaps 18 and 19.

These flaps, however, are provided in order to present a nice appearing garment and also to present a smooth outer surface over which other garments may be placed without tearing or causing protuberances therein. If the flaps 18 and 19 were connected in position along one longitudinal edge, they would move to an open position and become more or less wrinkled in use. To prevent this and also to provide a comparatively stiff and neat arrangement, the respective stays 14 and 14' are provided in the extensions 12 and 16 and the various spaced retaining stitches 15 are provided.

As shown in Fig. 6 there is a transverse retain-

ing stitching 15 between the adjacent groups of three eyelets, but it is obvious the stitchings could be arranged closer together or farther apart without departing from the spirit of the invention. This distance has proved to be satisfactory in ordinary use and it is therefore considered to be the best spacing.

The corset may be provided with other stays or various desired members without departing from the spirit of the invention, and the other stays used may be of steel or other material, but the stays 14 and 14' must be of material which will present a flexible supporting and stay structure and one through which the stitching 15 can readily pass.

By this construction and arrangement the eyelets cannot be seen through a thin dress and yet they are conveniently positioned so that the lacing can be adjusted to any desired extent, and so that the opening at the front of the corset may be comparatively great or may be very narrow.

As shown in Figs. 1 to 6, inclusive, the invention has been illustrated on the front of a corset, but if desired it may be used on the rear 25 of the corset as shown in Fig. 7. In this form of the corset any desired type of disengageable connecting means 6' may be used, the same being preferably of the type indicated by the numeral

6 in Fig. 2. The same arrangement of lacing and associated parts are presented at the rear, as shown in Fig. 2 at the front, with the flaps 18' and 19' covering the eyelets so as to present a nice, smooth appearance to the garment.

I claim:

A corset comprising a body having a pair of facing edges, a stiffening stay carried by said body adjacent each of said facing edges, said stays being of material capable of receiving stitching, a row of eyelets set back from each of said facing edges, a covering flap for each of said rows of eyelets and the stays adjacent thereto, and a plurality of spaced circumferentially extending rows of stitching extending from the edge of the respective flaps across the flaps and connecting the flaps for substantially their full width to said body whereby a plurality of pockets are presented, there being a plurality of eyelets in each pocket, said pockets being of sufficient length to permit lacings to be threaded through said eyelets without tearing the pockets and without permanently deforming said stiffening stays, said stays normally holding said facing edges and the edges of said flaps substantially taut.

JOSEPH J. KISPERT.
